UNITED STATES PATENT OFFICE.

JOHN DESJARDINS, OF MARINETTE, WISCONSIN.

RADIATOR ATTACHMENT.

1,155,997.

Specification of Letters Patent.

Patented Oct. 5, 1915.

Application filed January 14, 1914. Serial No. 812,117.

To all whom it may concern:

Be it known that I, JOHN DESJARDINS, a citizen of the United States, residing at Marinette, in the county of Marinette and State of Wisconsin, have invented new and useful Improvements in Radiator Attachments, of which the following is a specification.

This invention relates to radiator attachments; and it has for its primary object the provision of means for utilizing a large percentage of the waste heat.

Another object of the invention is the provision of a radiator attachment which will be constructed with a view to effectually causing the heat to be conducted to one or a plurality of rooms, as the occasion may demand or necessitate.

A further object of the invention is the provision of an attachment of this character which may be applied to the radiator without affecting the primary purpose of the radiator or a heater at a prescribed point. In other words, I contemplate the construction of a device as mentioned which may be used to utilize the heat and without affecting the heating efficiency of the radiator.

A still further object of the invention is the provision of a heating attachment for radiators which may be applied to any standard form of radiator and which may be connected to the room or rooms to be heated by a suitable flue which may be arranged within the wall or without the wall as may be found desirable.

A still further object of my invention is the provision of an attachment made and attached in such a manner that it does not allow all of the surplus heated air to be conveyed through the flue or flues to the adjacent room or rooms, thereby causing the balance of the heated air to force itself down and out, causing the cold air above the floor to be put into a rotary circulating movement. The result of this movement is to form a uniformity of temperature in the room in which the radiator is located.

A further object of my invention is to convey the heated air through a flume or flumes, said flume or flumes being neat in appearance, and circulation of air being controlled at both ends of said flume or flumes by means of a damper at lower end, near radiator, and at the other end by connection with register, in box, set in floor or partition.

With these and other objects in view, the invention consists of certain novel features of construction, combination and arrangement of parts, as will be hereinafter described and claimed.

In the accompanying drawings:—Figure 1 is a front view of the radiator, conventionally showing the application of the heating attachment thereto, and further illustrating the manner of causing the heat to be conducted from the radiator to the adjacent rooms; Fig. 2 is a vertical longitudinal section, taken on the line 2—2 of Fig. 1; Fig. 3 is a perspective view of the attachment removed from the radiator; Fig. 4 is an inverted perspective view thereof; and Fig. 5 is a section on the line 5—5 of Fig. 1.

The attachment is preferably in the form of a hood 1 having a crown or top wall 2, side walls 3 and end walls 4. The hood thus formed has a width slightly exceeding the width of the coils of the radiator, as shown particularly in Figs. 2 and 5 of the drawings, so that spaces 5 are formed between the sides 3 of the hood and the adjacent coils of the radiator. This arrangement is such that a proper circulation of air may be set up. The hood extends over all of the coils and like the sides, the ends 4 are spaced from the adjacent coils of the radiator. The hood is provided at spaced intervals with conducting tubes 6 and 6', the latter being extended in a horizontal direction and through the wall of the flue 9, as shown in Fig. 2, and it is thereby arranged to open into the adjacent lower room B conventionally illustrated in Fig. 2. The open end of the tube 6' is provided with a pivoted damper 10 of any suitable well known form which may be opened whereby the heat from the radiator may be conducted to said room B as will be understood. The other tube 6 also extends into the wall of the flue 9, and is provided with a closed end and a vertical opening 11, the latter having connection with a vertical tube 12 which extends upwardly in the flue 9 and which opens into a heat distributing member 12^a, the latter having branches which extend in opposite directions so as to open respectively into the rooms C and D. These branches are partly covered by grates 14 and pivoted damper plates 13, as also shown in Fig. 2. The tubes 6 and 6' are provided with pivoted dampers 15, which may be operated so as to prevent the heat from being conducted to

the points of discharge hereinbefore mentioned.

While the structure described herein is adapted to accommodate itself to the usual 5 rectangular radiator, it is advisable that it be understood that its design is immaterial and that it may be made so as to accommodate any well known form or design of radiator. It is also preferable that it be 10 understood that the heat conducting ducts or flues can be arranged wholly within the walls or without the walls as may be found desirable.

From the foregoing description, taken in 15 connection with the accompanying drawings, the construction and operation of the invention will be readily understood without requiring a more extended explanation.

Various changes in the form, proportion 20 and the minor details of construction may be resorted to without departing from the principle or sacrificing any of the advantages of this invention as claimed.

I claim:—

25 As a new article of manufacture, a radiator attachment including a single piece of

sheet metal bent to form a hood of substantially rectangular configuration, including a top, sides and end walls, the top wall of said portion being formed at spaced intervals along the longitudinal medial line thereof, with a pair of parallel spaced horizontally disposed tubes each having an opening therein, one of said tubes being disposed flush with one of the end walls of 30 said rectangular portion, while the other of the tubes being arranged flush with the opposite end walls and each protruding over and beyond one of the longitudinal side walls of said portion and above the plane of 35 the top wall thereof for the greater portion of their length, the opening of one tube being arranged at right angles to the opening of the other tube substantially as and for 40 the purpose specified.

45 In testimony whereof I affix my signature in presence of two witnesses.

JOHN DESJARDINS.
